ATTORNEY

UNITED STATES PATENT OFFICE.

DAVID S. WEGG, OF CHICAGO, ILLINOIS.

DESIGN FOR A CEILING-LIGHT.

SPECIFICATION forming part of Design No. 34,175, dated March 5, 1901.

Application filed December 24, 1900. Serial No. 40,986. Term of patent 7 years.

To all whom it may concern:

Be it known that I, DAVID S. WEGG, a citizen of the United States, and a resident of Chicago, in the county of Cook and State of Illinois, have invented and produced a new and original Design for Ceiling-Lights, of which the following is a specification.

My new design relates to that class of illuminating-fixtures which are directly under the ceiling or against the walls of a room and are known in the trade as "ceiling-lights."

The accompanying drawings, forming part of this specification, show my newly-designed ceiling-light.

Figure 1 is a side view, and Fig. 2 is an inverted plan view as seen directly from underneath.

1 is the so-called "holder."
2 is a glass dish, round in cross-section, of peculiar shape and of a translucent opalescent glass roughed on its inner surface. The light emitted by the cluster of lamps within the dish is diffused, and the individual lamps or jets are invisible through the glass.

To conceal the so-called "holder" as much

as possible, I shape the dish with a flaring flange 3 at the top. The outline of the dish then continues outward and downward in a circular curve. At the lowest point of this curve and on a vertical line with the center 30 thereof the outline continues toward the center of the dish in a concaved curve, as shown by the dotted lines in Fig. 1, forming an annular concavity around the central point 4, which has the shape of an inverted cone. 35

The ceiling-light shown and described has a pleasing and ornamental appearance.

Such being a description of my newly-invented design, what I claim as new, and desire to secure by Letters Patent, is— 40

The design for a ceiling-light as herein shown and described.

Signed at Chicago, in the county of Cook and State of Illinois, this 19th day of December, A. D. 1900.

DAVID S. WEGG.
